UNITED STATES PATENT OFFICE.

ANDERS GUSTAF LUNDQUIST AND KARL JOHAN ALGOT JONSON, OF STOCKHOLM,
SWEDEN, ASSIGNEES TO AKTIEBOLAGET SKANDINAVISKA ORGEL-OCK PIANO-
FABRIKEN, OF STOCKHOLM, SWEDEN, A CORPORATION.

REED-ORGAN SWELL.

1,415,665.

Specification of Letters Patent.

Patented May 9, 1922.

Application filed October 28, 1920. Serial No. 420,305.

To all whom it may concern:

Be it known that we, ANDERS GUSTAF LUNDQUIST and KARL JOHAN ALGOT JONSON, both subjects of the King of Sweden, and residing at Stockholm, Sweden, have invented 5 certain new and useful Improvements in Reed-Organ Swells, of which the following is a specification.

This invention relates to organs and like 10 musical instruments, and has for its purpose to provide means for facilitating a slow and continuous variation of the volume of the tone (crescendo and diminuendo). In small organs this was heretofore effected in a most 15 imperfect manner by means of a contrivance resembling in construction a common mute, by means of which the quantity of the air admitted to the reeds is varied. Such mutes do not allow of a slow increase of the air 20 flowing in. According to the present invention, a slow and continuous variation of the volume of the tone is obtained by forming the valve members like shutters or the like which are slidably arranged over the air- 25 ports, and by the movement of which the said air-ports may be gradually exposed or shut up. The contrivance is preferably so arranged that each shutter will control a plurality of elongated tapering apertures 30 arranged in one or more rows in such a manner that the various apertures extend in the direction of movement of the shutter, the latter being provided with a corresponding number of air-ports, preferably formed in 35 the same way, which air-ports are gradually brought to register with the first-mentioned apertures when the shutter is being displaced.

The invention is illustrated in the accompanying drawing, in which Fig. 1 is a plan view, and Fig. 2 a cross section on the line 2—2 in Fig. 1, of a reed board for a chamber-organ provided with a contrivance according to the invention.

The reed board, the bottom 1 of which forms the cover of a wind-chest 2, comprises a wooden board 3 provided with transversal, horizontal air-passages 4 opening at the stepped edges of the board 3, and communicating at their inner ends with vertical channels 5 which, in turn are in communication with the wind-chest in which vacuum

is produced in known manner by actuating the pedals. Arranged within the horizontal air-passages 4 are the tongues 8 supported 55 by a frame-like reed-block 7, the inner free ends of the tongues 8 being situated right over the corresponding vertical channels 5. In the example shown in the drawing, the tongues are arranged in four rows, that is to 60 say two on either side of the board 3, and in two different horizontal planes. The mouths of the horizontal passages 4 are covered by mutes hinged at their upper edges, the said mutes being actuated by means of the organ-stops. 65

The passages 4 are obstructed outwards on either side of the tone box not only by the said flaps 9, but also by a swell 10 the so-called forte-swell, adapted to swing on the hinge 22, and the forte-swells coat with the walls 11 arranged at the ends of the reed board to form a casing which surrounds the mouth of the passages 4. The admission of the air is controlled according to the invention by means of slides or shutters 13 guided by guiding-members 12, the said shutters normally closing a plurality of air ports 14 arranged in two rows and in zig-zag with respect to each other, which openings are of an elongated shape, tapering in the direction of movement of the slide or shutter. The slides 13 are provided with apertures 15 shaped and arranged in a similar manner, and adapted to gradually expose the openings 14 by a displacement of 80 the slide, so as to slowly increase the total area of admission of the air. 85

The inner vertical channels 5 extend through the entire board 3, and the upper 90 mouths thereof are covered by hinged flaps 16 actuated by the organ-stops. Arranged above each of the inner rows of vertical channels 5 are boxes or casings 17 provided with a single row of air-ports 18, which are 95 normally covered by slides or shutters 20 guided by guides 19, the said slides being provided with air-ports 21 of the same shape as the apertures 18 in the covers.

The slides or shutters 13 and 20 are connected by means of a suitable transmission arrangement (not shown in the drawing) with an operating member in the form of a lever, which is so arranged that it may be 100

actuated by the knee or the foot of the player, and by means of which the slides may be displaced in the longitudinal direction to vary the volume of the tone in the 5 manner hereinabove described.

In connection with the foregoing it is understood that slideable shutters have been provided with apertures for varying the volume of tone in organs. However, in this 10 invention, the essential difference resides in the tapered shape of these apertures. Extensive experiments have been made to obtain a construction whereby the tone of the organ may be easily graduated within a 15 wide range and it has been discovered that this is practically impossible when using round apertures, such apertures having practically the same effect as the usual pivotally mounted mutes. The graduation attained 20 can only be effectively produced by the employment of elongated tapering apertures and this feature must therefore be considered very essential.

What we claim as new and desire to se-

cure by Letters Patent of the United States 25 is:—

1. A reed organ or the like instrument in which the tongues are mounted within a casting provided with air-openings or apertures and one or more valve members adapted to 30 control these apertures, the said valve members consisting of slideable shutters provided with a corresponding number of apertures which are gradually brought into registration with the first mentioned apertures when 35 the shutter is displaced, the apertures tapering substantially to a point.

2. An arrangement in accordance with 40 claim 1 wherein the apertures are arranged in zigzag in two or more rows.

In witness whereof we have hereunto set our hands in the presence of two witnesses.

ANDERS GUSTAF LUNDQUIST.
KARL JOHAN ALGOT JONSON.
